SPINDLE PRESS

Otto Kienzle, Berlin-Sudende, Germany

Application January 21, 1937, Serial No. 121,719
In Germany January 23, 1936

10 Claims. (Cl. 100—70)

This invention relates to a spindle-press or pressure exerting device and more particularly to such a type thereof which includes an electric motor as a drive and wherein the driving element of the motor is preferably arranged at a permanent height with relation to the fly-wheel of the press.

In known machines of this type, the motor is stationarily mounted on the framework of the machine, while the fly-wheel, which always remains at the same height, revolves a nut which can be rotated but cannot be shifted in the framework, so that the lifting spindle guided by the nut and supporting the press-stock or ram will be screwed downwards or upwards if the fly-wheel be rotated. It appears, however, that this arrangement requires a very considerable length of threads so that the framework and, thus, the entire mechanism will be of undue height. On the other hand, the unfavourable friction conditions and the extended expenditure of energy within the frame-work will also require a considerable expenditure of power.

The present invention relates to improvements in or relating to mechanisms of the aforesaid character, which avoids the drawbacks referred to. It is a main object of this invention to diminish the structural height of a spindle-press and to lower the losses of energy caused by friction. Another object of my invention refers to arrangements wherein the driving motor of the press follows the strokes of the stock or ram. A still further feature resides in the provision of mechanically acting stops or electric contacts, for example, both adapted to control the stroke of the press-stock.

More particularly, the invention refers to presses wherein the electric-motor is mounted on a shoe or sliding member guided in the framework, and which follows the strokes of the ram, said sliding member rotatably bearing the spindle without axial displacement, whereas the spindle connected to the fly-wheel revolves within the nut stationarily mounted in the frame-work.

Last but not least, the invention provides means for automatically disconnecting the motor from the spindle at the moment of the impress, if for any reason the stop or contact finger arranged for disconnecting purposes fails to function. In this way, the threads of the press and likewise the motor will be effectively saved from damages.

The invention will now be described more precisely by way of example in and by the accompanying drawings in which

Fig. 1 is a side elevation with parts broken away, of a spindle-press wherein the motor is mounted sideways of a sliding member.

Fig. 2 is a fragmentary side elevation of the same, illustrating the position of the motor at the moment when the stock or ram meets the piece of work.

Fig. 3 is a fragmentary sectional view taken on line 3—3 of Fig. 1;

Fig. 4 is a side elevation, with parts broken away, of a modified form of press wherein the motor and the spindle are arranged coaxially.

Figs. 5a to 5d inclusive illustrate the operation of the electric control mechanism for automatically disconnecting the motor from the spindle; 15

Figs. 6a to 6d inclusive illustrate the operation of the electric control mechanism for controlling the operation of the motor; and

Figs. 7a and 7b illustrate the operation of the electric contact for actuating the spindle brake 20 mechanism.

Like elements are designated by like references.

In Fig. 1 the threaded spindle 1 is guided within the frame-work 2 by a nut or threaded portion 8 and is, in addition, rotatably, but not 25 shiftably supported at the top and at the bottom by means of a shoe or sliding member 4. The sliding member 4 is shiftably mounted preferably in tapering or dovetail guides 15 of the frame 2 so that it can follow the strokes of the spindle 30 1 and of the press ram 3 connected thereto. In the arrangement of Fig. 1, the upper end of the spindle 1 carries the flywheel 6 provided with a frictional coating 16. The motor 1 which is preferably of the reversible type, is mounted on 35 the sliding member 4 which may oscillate upwards and downwards, said motor being tiltable by its base plate 18 around a pivot 17 horizontally provided in the sliding member 4. The motor is provided with a drive pulley 5 which is 40 frictionally engaged with the periphery of the flywheel 6 and, thus, with the spindle 1. In order that the motor 1 will not tilt by its own weight around the pivot 17 into the position shown in Fig. 2, the base plate 18 of the motor is kept by 45 means of one or more springs 19 against the bearing surface of the sliding member 4. This arrangement for mounting the motor provides a damping means against shocks.

In order that the shock of impact caused by 50 the stock or ram 3 striking against the piece of work 21 will not damage the motor, the latter is adapted to be disconnected from the fly-wheel 6 shortly before the shock of impact, as appearing in Fig. 2. This is effected by the engagement 55

of a contact finger or stop 9 with a lug or projection 10, the former being vertically adjustable on bar 22 in any suitable manner in correspondence with the desired stroke of the press spindle 5 and acting electrically upon means 20 provided for disconnecting the motor as will hereinafter appear more in detail.

Around the spindle 7, there is arranged a brake 11 which can retain the spindle and, thus, the 10 ram in any desired upper position. The said 15 brake may be operated in known manner, for example, by electromagnetic means. It is engaged when the contact finger or stop 14 is actuated, that is, shortly before the stock or ram 3 has attained its desired upper position. The motor 1, 20 on the other hand, has already been thrown off during the lifting of the stock 3 by another contact finger 12 acting prior to the member 14, that is in such time that the stock 3 runs upwards under the mere inertia of the fly-wheel 6 and is, thus, almost stopped when the brake 11 is put into operation. Likewise, the ram can be stopped in the upper position by one of these controlling measures alone.

25 The control circuit for tilting the motor 1 and for disconnecting the motor and actuating the brake mechanism is more or less conventional arrangement and is illustrated in Figs. 5a, b, c and d; and 6a, b, c and d; and 7a and b.

30 Fig. 5a shows the operation of the contact 9 for actuating the lifting mechanism 20 in Fig. 2. The contact finger 9 is tiltable in a housing 29 about the axis 30 and resiliently mounted by means of springs 31 at both sides thereof. The 35 electric circuit is connected at the movable contact 32 on the one end, and on the other at an insulated counter-contact 33 disposed in housing 29. Fig. 5a shows the moment at which the contact finger 9, descending together with the press 40 bars has almost reached the fixed stop 10. In Fig. 5b the contact finger 9 is in engagement with the stop 10 by means of which it is tilted during the continued descent of member 4, thereby closing contact 32-33. At this moment a circuit is 45 closed to the magnet 20, the core 34 of which is drawn into the magnet coil and the motor 1 is forced away from the fly wheel 6 on the pivot 17 in opposition to the force of spring 18. At the very next instant, the impact of the press bars 50 3 on the object 21 takes place and the contacts assume the positions shown in Fig. 5c.

55 Finger 9 has at this moment just passed the stop 10 so that the circuit to the magnet 20 is broken. Motor 1 is then automatically reversed by any conventional mechanism and again returned to engagement with the fly wheel 6, so that the press bar again ascends by reversal of the rotational direction of the spindle 7. Contact finger 9 thereby again passes stop 10 as shown in Fig. 5d, without acting on magnet 20.

60 In the re-ascent of the press bar and there-with the slide 4, contacts 12 and 14 enter into operation. The contact finger 12 (referring to Figs. 6a to 6d) is similar to the contact finger 9 and is resiliently suspended at both sides. As shown in Fig. 6a, finger 12 approaches the fixed stop 13 from below and in this position the circuit to the switch magnet 36, is opened. Fig. 6b shows the moment at which the contact finger 12 65 engages stop 13 and is tilted to close the contact 35. Simultaneously the switch magnet 36 is energized and cuts out the drive motor by opening contact 37. At the same time, contact 38 lying in the circuit for the electromagnet of the brake 11, is closed, the current bridge 39 now contacting

5 with contact 38. In Fig. 6c the upper movement is continued and finger 12 is above stop 13, in which position contact 35 is again open. Notwithstanding magnet 36, the bridge 39 is without current, remaining in its assumed position, so that the circuit for the drive motor remains open. The motor can again be connected only by closing a hand switch 40 shown in Fig. 6d. Thereby 10 a circuit for a second switch magnet 41 is completed so that said magnet again applies bridge 39 on contacts 37 and removes it from contacts 38.

15 Figs. 7a and 7b show the operation of the contact finger 14 for connecting the brake. Finger 14 is spring mounted at both sides and pivotally disposed as in the case of fingers 9 and 12, said finger actuating contact 42 which lies in the circuit of the brake magnet 11, in which the two contacts 38 are also arranged. Shortly after finger 12 has come in contact with stop 13, as 20 shown in Figs. 6b and 6c, finger 14 acts on stop 13, which it also approaches from below, as the spindle 7 continues to ascend through the inertia of the fly wheel, even after the motor is cut off. Fig. 7a shows the moment at which finger 14 25 has almost passed into contact with stop 13. Fig. 7b shows the next moment at which the contact finger 14 is tilted under the action of stop 13, so that contact 42 for the brake magnet 11 is closed. As shown in Figs. 6b and 6c contacts 30 38 are also closed at this time, so that the brake is thus actuated, which finally holds the spindle 11 fast in its upper position. When the motor is again energized as shown in Fig. 6d the contacts 35 38, Fig. 7b, are again opened so that the brake is released and spindle 7 can descend for a new impact through the action of the drive motor.

35 The contact fingers or stops 12 and 14 provided for stopping the motor and for operating the brake may be adjusted on the sliding member 4 according to length and position of the sliding member. So, for instance, they can be shifted and locked on a bar 22 vertically arranged on the sliding member 4. Instead of the bar 22, there could also be arranged in the sliding member a groove with which are engaging the shiftable contact fingers or stops. At the same time, the members 12 and 14 could be rigidly connected together at a definite distance, like appearing from the drawings, so that they can be shifted and 40 adjusted commonly. The distance of these contacts or stops from each other can also be regulable; it corresponds with the average time interval between stopping the motor and operating the brake.

45 The contact finger or stop 9 is arranged to engage with a stop or cam 10 rigidly connected to the top of the frame work. The contact fingers or stops 12 and 14 are acted upon by a cam 13 likewise rigidly attached to the framework of the 50 machine.

55 By the contact fingers or stops 9, 12 and 14 adjustably arranged on the sliding member 4, the position and length of the stroke may be arbitrarily regulated. So, it is, for instance, not always necessary to lift the ram to its uppermost position. For, apart from the requirement that the piece of work 21 can be conveniently put into and removed from the press, the press stock needs only to be lifted to such a height that, while the stock is 60 dropped, sufficient time is available for storing the 65 energy in the fly-wheel.

70 Thus, by the improved drive a shorter falling period of the ram, if compared with known presses, may be attained. The extent of the stroke and 75

the force of the shock can arbitrarily be adjusted. The improved press shows, besides, regarding its handling a sensibility which could not be attained up to now.

5 The same advantages can also be ascribed to the embodiment shown in Fig. 4. Here, the motor is arranged axially to and above the spindle 7. It is secured to the sliding member 4 in such a manner that its rotatable portion or armature 23 is coupled with or forms the fly-wheel, while the stationary portion or field 24 of the motor is connected with the correspondingly formed head 25 of the sliding member 4. The flywheel portion 23 is preferably rotatably supported upon the sliding member by ball collar thrust-bearings 26.

In this form of the invention the tilting finger 9 and fixed stop 10 are eliminated but the fingers 12 and 14 cooperate with the fixed stop 13 in the same manner as those heretofore described. 20 Hence when the ram 3 engages the piece of work 21 the motor is automatically disconnected from the spindle 7 by the operation of finger 12. The motor is then reversed and when the spindle reaches the end of the desired upward stroke the 25 brake 11 is actuated through the operation of the finger 14.

It is obvious that the invention is not restricted to the embodiments described in connection with the drawings, but rather numerous constructional 30 alterations may be made without departing from the spirit of this invention.

Having thus described by invention, what I claim as new and desire to secure by Letters Patent, is:

35 1. A spindle press comprising a framework, a stationary threaded portion carried by said framework, a sliding member mounted in guide ways on said framework and terminating at one end in a press ram, a screw threaded spindle engaging said threaded portion and being rotatably supported by said sliding member with one end operatively engaging said ram, the other end of said spindle carrying a fly wheel, a reversible electric motor mounted on said sliding member and 40 adapted to rotate said spindle, whereby said motor and sliding member are adapted to follow the strokes of said spindle.

2. A spindle press comprising a framework, a stationary threaded portion carried by said framework, 50 work, a sliding member mounted in guide ways on said framework and terminating at one end in a press ram, a screw threaded spindle engaging said threaded portion and being rotatably supported by said sliding member with one end operatively engaging said ram, the other end of said spindle carrying a fly wheel, a reversible electric motor mounted on said sliding member and adapted to 55 rotate said spindle, whereby said motor and sliding member are adapted to follow the strokes of said spindle, coupling means interposed between said motor and said spindle and means for disconnecting the motor from the spindle just prior to the moment said ram contacts the work piece.

3. A spindle press as claimed in claim 2 including a contact element arranged on said sliding member and adapted to cooperate with a stop on said framework to control said disconnecting means.

4. A spindle press as claimed in claim 2 including a contact element arranged on said sliding member and adapted to cooperate with a stop on said framework to control said disconnecting means, said contact element being adjustable on said sliding member to correspond with the desired extension and position of the spindle stroke.

5 5. A spindle press comprising a framework, a stationary threaded portion carried by said framework, a sliding member mounted in guide ways on said framework and terminating at one end in a press ram, a screw threaded spindle engaging said threaded portion and rotatably supported by said sliding member with one end operatively engaging said ram, the other end of said spindle carrying a fly wheel, a reversible electric motor mounted laterally on said sliding member, a driving wheel 10 mounted on the shaft of said motor and having a peripheral frictional engagement with said fly wheel to rotate said spindle and means for moving said driving wheel out of contact with said fly wheel just prior to the engagement of said ram 15 with the work piece.

6. A spindle press as claimed in claim 5 wherein said motor is pivotally mounted by its base plate on said sliding member, spring means normally tending to maintain engagement between 20 said driving wheel and fly wheel and an automatic shifting device arranged between the sliding member and the base plate of said motor for tilting the motor and driving wheel away from said fly wheel in opposition to said spring means. 25

7. A spindle press comprising a framework, a stationary threaded portion carried by said framework, a sliding member mounted in guide ways on said framework and terminating at one end in a press ram, a screw threaded spindle engaging said threaded portion and rotatably supported by said sliding member with one end operatively engaging said ram, the other end of said spindle carrying a fly wheel, a reversible electric motor mounted on said sliding member and 30 adapted to rotate said spindle, said sliding member and motor adapted to follow the strokes of said spindle, coupling means interposed between said motor and said spindle, means for disconnecting the motor from said spindle just prior to the impact of said ram on said work piece, a 35 brake adapted to engage said spindle and means for de-energizing said motor and then operating said brake just prior to the moment said press ram reaches the desired upper position. 45

8. A spindle press as claimed in claim 7 including a series of contact elements adjustable on said sliding member and adapted to cooperate with complementary stops on said framework to actuate said disconnecting means, said motor de-energizing means and said spindle brake respectively. 50

9. A spindle press comprising a framework, a stationary threaded portion carried by said framework, a sliding member mounted in guide ways on said framework and terminating at one end in a press ram, a screw threaded spindle engaging said threaded portion and rotatably supported by said sliding member with one end operatively engaging said ram, the other end of said spindle carrying a fly wheel, a reversible electric motor mounted on said sliding member, coupling means interposed between said motor and spindle, means for disconnecting said motor from said spindle just prior to the impact of said ram on the work piece whereby the completion of the down stroke of said spindle is brought about through the inertia of said fly wheel, a brake for said spindle, means operable upon the reversal of said motor, for de-energizing the motor, just prior to the completion of the upstroke of said spindle under the influence of said fly wheel, and means for operating said brake just prior to the moment said spindle has reached the desired upper position. 75

10. A spindle press comprising a framework, a stationary threaded portion carried by said framework, a sliding member mounted in guide ways on said framework and terminating at one end in a press ram, a screw threaded spindle engaging said threaded portion and being rotatably supported by said sliding member with one end operatively engaging said ram, a fly wheel operatively connected to the other end of said

spindle, a reversible electric motor mounted on said sliding member co-axial with said spindle, the rotor of said motor constituting said fly wheel, said sliding member and motor being adapted to follow the strokes of said spindle and means for disconnecting said motor just prior to the moment said ram contacts the work piece.

OTTO KIENZLE.
